NECK SEAL FOR ARTIFICIAL RESPIRATORS

Ludwig Schlobohm and Alvin J. Farrar, Cleveland, Ohio, assignors to The Van Dorn Iron Works Company, Cleveland, Ohio, a corporation of Ohio

Application July 14, 1942, Serial No. 450,882

2 Claims. (Cl. 128—28)

This invention relates to neck seals for artificial respirators of the general type shown in a copending application, Ser. No. 447,559, filed June 18, 1942, and, among other objects, aims to provide an inflatable collar or tubular seal associated with a flexible diaphragm in the head opening of the respirator. The idea is to provide a seal similar to the inner tube of a pneumatic tire which can be inflated very quickly after the patient's head is inserted through the deflated tube, to thereby prevent the escape of air from the body chamber of the respirator. Another aim is to provide a neck seal tube of this type having provision for deflation to permit the quick removal of the patient.

Other aims and advantages of the invention will appear in the specification, when considered in connection with the accompanying drawings, wherein:

Fig. 1 is a side elevation of a respirator;
Fig. 2 is a front elevation of the neck seal of the respirator;

Fig. 3 is a section taken on the line 3—3 of Fig. 2; and

Fig. 4 is a cross sectional view taken on the line 4—4 of Fig. 2 on an enlarged scale.

Referring particularly to the drawings, the improved neck seal is shown as being applied to a portable respirator illustrated generally in Fig. 1, and which is similar to that shown in the aforesaid copending application; although it will be understood that it is applicable to other forms of respirators. It is not necessary to refer to all of the details of the respirator shown. It is sufficient to state that it embodies a portable casing 10 having an upper body chamber which is covered by a semi-cylindrical hood 11 hinged to one side of the casing. The back side of the hood carries a body receiving diaphragm 12 and a supporting table 13 is shown as being removably mounted on the back of the casing to support the body of a patient. A head rest 14 is adjustably and removably mounted on the front wall of the casing. The upper end of the casing likewise carries a body supporting pad (not shown), so that a patient may be placed in the chamber when the hood 11 is raised, as explained in the copending application.

In this instance, the front end of the hood 11 has a metal wall 15 within which there is provided a rectangular opening 16 extending through its lower edge so that the hood can be closed over the patient's body before the neck seal is applied. Incidentally, provision may be made by means of a slotted opening in the body

diaphragm 12 to permit the body diaphragm to close on the patient and then be adjusted.

Referring to Fig. 3, there is shown a gasket frame 17 carrying a rubber or other deformable gasket 18 adapted to be compressed against the front face or wall 15 of the casing. The neck seal is carried by a pair of sponge rubber diaphragms 19 which are clamped to the gasket frame 17 by angle members 20 and stud bolts 21 projecting outwardly from the channel frames 17 carrying the gaskets. The sponge rubber diaphragms 19 are thus mounted in a rigid metal frame structure adapted to be clamped against the front wall of the casing by means of opposed hand clamps 22, the gaskets 18 providing an effective seal to prevent escape of air.

The flexible diaphragm sheets 19 may, of course, be made of any other suitable material and they have a circular opening 23 within which there is mounted an inflatable latex or other elastic tube 24 secured in place by means of an inside frame member which may be made of rubber or other flexible material. This inside frame member is substantially T-shaped in cross section having an annular fin 25 preferably cemented between the two sheets 19. The outer periphery of the tube is preferably cemented to the cross flange 26; although it is contemplated that it may be vulcanized on the tube so that the fin 25 is integral with the tube. This arrangement prevents the tube from being blown out of the tube opening in the diaphragm due to the pulsating pressure in the respirator chamber.

The tube is shown as being provided with an ordinary bicycle inflating valve stem 27 and a manually operable inflating bulb 28 is attached to it by a tube 29. Likewise, the tube 24 has an exhaust valve stem 30 through which air may escape when the valve is opened or depressed.

The valve in stem 30 may also be like an ordinary bicycle valve.

From the foregoing description, it will be understood that after a patient is inserted in the chamber and the body seal adjusted, the neck seal assembly is then applied by inserting it over the patient's head with the tube 24 deflated. The frame is then fastened against the outer face 15 of the hood by the hand operated clamps 22. Then the tube is inflated by repeatedly squeezing the bulb 28 so that the tube engages the neck of the patient to make an airtight seal. When the patient is removed the tube is deflated by depressing the valve in stem 30 and the neck seal frame assembly is removed over the head 55 of the patient.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. A neck seal for an artificial respirator comprising a pair of superposed flexible diaphragms mounted in the respirator having an opening therein, a flexible frame member secured between the pair of diaphragms and having a flange pro-

jecting into the opening in said diaphragms; and an elastic, hollow, ring-shaped tube seated in the flange projecting portion of the frame and adapted to be inflated to fit snugly around the neck of a patient.

2. A neck seal according to claim 1, in which the flexible frame member is substantially T-shaped in cross section with the stem of the T between the diaphragms and the upper cross part 10 projects into the opening and to which the tube is secured.
